United States Patent Office

Des. 185,873
Patented Aug. 11, 1959

185,873

PLATE

Victor J. Bergeron, Orinda, Calif.

Application March 18, 1959, Serial No. 55,043

Term of patent 14 years

(Cl. D44—15)

FIG. 1

The bottom of the plate shown in Figures 1 and 2 is plain and unornamented.

I claim:

An ornamental design for a plate, as shown and described.
